REFRIGERATING MACHINE

Harley H. Bixler, Schenectady, N. Y., assignor
to General Electric Company, a corporation of
New York

Application September 24, 1935, Serial No. 41,905

9 Claims. (Cl. 62—115)

My invention relates to refrigerating machines. Refrigerating machines of the compression type usually include a refrigerant compressor in which a vaporized refrigerant, such as methyl formate, is compressed and which then flows to a condenser where it is liquefied. The liquefied refrigerant is supplied to an evaporator through a float valve or other flow controlling device. The interior of the evaporator is maintained at low pressure by the compressor and the absorption of heat by the liquid refrigerant in the evaporator causes the same to vaporize, the vaporized refrigerant being then returned to the compressor. This cycle is continued until the temperature of the compartment in which the evaporator is located is lowered to the desired value. Difficulty has been encountered in the operation of such refrigerating machines in that gases, which are non-condensable at pressures and temperatures encountered in an ordinary refrigerating machine, sometimes become mixed with the refrigerant. This may result when methyl chloride is used as the refrigerant, for example, due to the partial disintegration of the methyl formate into carbon monoxide and carbon dioxide, each of these latter gases being noncondensable at ordinary pressures and temperatures had in a refrigerating machine. Such non-condensable gases collect in the condenser and float valve casing, or other liquid refrigerant receiver chamber and tend to prevent the normal condensation of the compressed vaporized refrigerant.

It is an object of my invention to provide an arrangement in a refrigerating machine of the type described for preventing the collection of non-condensable gases in the condenser thereof.

Another object of my invention is to provide an improved arrangement for inducing a rapid circulation of refrigerant through the condenser of a refrigerating machine of the type described.

Another object of my invention is to provide for the carrying out of a method of operation of a refrigerating machine in such manner as to prevent the static accumulation of non-condensable gases in the system which would interfere with its operation.

Further objects and advantages of my invention will become apparent as the following description proceeds, and the features of novelty which characterize my invention are pointed out with particularity in the claims annexed to and forming a part of this specification.

For a better understanding of my invention reference may be had to the accompanying drawing, in which Fig. 1 is a side elevation partly in

section of a refrigerating machine of the household type embodying my invention, and Fig. 2 is a side elevation partly in section of a modified form of refrigerating machine of the household type embodying my invention.

5

Referring to the drawing, I have shown in Fig. 1 a refrigerating machine designed for household use which includes a rotary type compressor 10, which is connected to a vertical driving shaft 11 of an electric driving motor 12. Vaporized refrigerant compressed by the compressor 10 is liquefied in a natural draft air-cooled condenser 13 and is then supplied through a flow-controlling float valve located in the float valve casing 14 to a flooded type evaporator 15. The liquid refrigerant in the evaporator 15 is vaporized by the absorption of heat from the contents of the compartment in which the evaporator is located, and the refrigerant thus vaporized is returned to the compressor 10. The entire refrigerating machine is supported on a removable heat-insulated top wall 16 of the compartment in which the evaporator 15 is located.

The compressor 10 is supported in a cylindrical hermetically sealed casing 17, made of steel 25 or the like, on a series of vertical helical compression springs 18. The casing 17 includes complementary upper and low sections 19 and 20, respectively, the adjacent edges of which are welded together in abutting relation as indicated at 21. 30 A reinforcing strip 22 is positioned within the casing 17 and covers the inner side of the welded seam 21. The compressor 10 is provided with an integral open top supporting casing 23 on the top thereof, which supports the electric driving motor 35 12. A series of horizontal feet 24 extend laterally from the sides of the supporting casing 23 and the tops of the supporting springs 18 are secured thereto by suitable plugs and bolts 25.

Vaporized refrigerant, such as methyl formate, 40 is compressed by the refrigerant compressor 10 and is discharged therefrom through a suitable discharge port thereof into the interior of the casing 17. The gaseous refrigerant in the casing 17 flows therefrom through a conduit 26 which 45 communicates with the interior of the casing and with the refrigerant circulatory passages of the condenser 13. The condenser 13 is cylindrical in shape and surrounds the casing 17, being made up of complementary cylindrical sheets of metal 50 27 and 28. A refrigerant circulatory passage 29 is formed between the inner and outer sheets 27 and 28 by complementary indentations 30 and 31 formed therein. The refrigerant circulatory passage 29 is preferably divided into upper and lower 55

sections which are connected in series by a U-shaped conduit 32. The inner and outer sheets are rigidly secured together by line welding, a series of closely spaced spot welds, or otherwise, 5 about the edges thereof and between the indentations 30 and 31 formed therein throughout the length of such indentations. The condenser 13 thus formed is supported on a series of radial heat-conducting fins 33 which extend between 10 the outer side walls of the casing 17 and the inner walls of the condenser 13. Cooling air circulates upwardly over the surfaces of the condenser 13 and fins 33 due to natural draft, and the refrigerant circulating through the passage 29 is cooled 15 thereby and liquefied. The refrigerant thus liquefied in the condenser 13 flows therefrom through a conduit 34 to the casing or chamber 14 in which a flow-controlling float valve is located.

I provide an arrangement for conveying the 20 vaporized refrigerant or other fluid within the casing 17 through the conduit 26 and condenser 13 independently of the pressure prevailing in the casing 17. As illustrated in Fig. 1 a centrifugal fan 35 is secured to the upper end of the 25 vertical driving shaft 11 of the electric motor 12 and is driven thereby. The inner end of the conduit 26 is located closely adjacent the periphery of the centrifugal fan 35 and, as a consequence, fluid within the casing 17 is blown into 30 the conduit 26 upon rotation of the fan 35. Refrigerant is thus positively and rapidly circulated through the refrigerant circulatory passage 29 of the condenser 13, and the heat transfer between the refrigerant flowing through the 35 condenser 13 and the cooling air flowing over its surfaces is improved. The fan 35 also serves to circulate compressed gaseous refrigerant or other fluid within the casing 17 over the surfaces of the compressor 10 and driving motor 12. This 40 circulation of fluid over the surfaces of the compressor and driving motor serves to transfer heat therefrom to the walls of the casing 17 from which it is dissipated to the surrounding cooling air circulating thereover due to natural draft. 45 The fan 35 thus serves the double purpose of cooling the compressor 10 and driving motor 12 therefor, and circulating refrigerant through the condenser 13.

I also provide an arrangement for conveying 50 non-condensable gases from the float valve casing 14 to the interior of the hermetically sealed casing 17. Gases which are non-condensable at the 55 pressures and temperatures ordinarily encountered in a refrigerating machine are frequently mixed with the methyl formate, or other vaporizable refrigerant, in the machine. Such non-condensable gases may be formed in the machine due to the disintegration of the refrigerant. In the case of methyl formate it has been found that 60 carbon monoxide and carbon dioxide are frequently formed after the refrigerant has been used for some time in the refrigerating machine. As a consequence, the casing 17 ordinarily contains a fluid mixture of compressed vaporized refrigerant and non-condensable gases. If some provision is not made for returning the non-condensable gases to the compressor 10 from the float valve casing 14, they will accumulate in the condenser 13 and in the float valve casing 14 until the condenser is partially or wholly filled 65 by such non-condensable gases, thus obstructing the flow of liquid refrigerant and seriously impairing the liquefying action of the condenser.

In the form of my invention illustrated in Fig. 75 1 a conduit 35 is provided which communicates

with the interior of the float valve casing 14 above the normal liquid level therein, which is indicated by dot-dash line 43, and with the interior of the hermetically sealed casing 17 above the level of the lubricating oil 35a in the bottom 5 thereof. The float valve casing 14 thus receives liquefied refrigerant and non-condensable gases flowing from the condenser 13 and they are separated by gravity in the float valve casing. The non-condensable gases which collect above the 10 normal level of the liquid refrigerant in the float valve casing 14 flow upwardly through the conduit 35 into the casing 17. Since the casing 17 is of much greater cubic capacity than the refrigerant circulatory passage 29 of the condenser 15 13, an undue concentration of non-condensable gas is not had in the casing 17. Also, since the fan 35 continuously circulates refrigerant and non-condensable gases through the condenser 13, the non-condensable gases do not have an 20 opportunity to collect therein but are moved rapidly therethrough and returned to the casing 17 through the conduit 35. By this arrangement I am enabled to carry out a method of operating the refrigerating machine such that non-condensable gases will not accumulate in the condenser 29 of the machine and prevent the flow of compressed refrigerant thereto during operation 25 of the machine.

The liquefied refrigerant accumulated in the 30 float valve casing 14 is supplied therefrom through a conduit 36 to the refrigerant circulatory passages formed by indentations 37 in an outer sheet of the sheet metal evaporator 15. The evaporator 15 is made up of inner and outer 35 sheets of metal which are welded or otherwise rigidly secured together about the edges thereof and between the indentations formed therein, and a cylindrical longitudinal header 38 is formed in the upper portion of the evaporator 15. The 40 upper ends of the passages formed by the indentations 37 communicate with the header 38 below the normal liquid level therein, the header 38 being ordinarily maintained about half full of liquid refrigerant. The liquid refrigerant in 45 the flooded evaporator 15 is vaporized by the absorption of heat from the contents of the compartment in which it is located, and the refrigerant thus vaporized is collected in the header 38 above the level of the liquid refrigerant there- 50 in. The vaporized refrigerant thus collected in the header 38 is returned to the intake port of the compressor 10 through an exhaust conduit 39. The cycle of operation described above is 55 repeated and continued until the temperature of the compartment in which the evaporator 15 is located is lowered to a desired value.

The refrigerating machine shown in Fig. 2 embodying my invention is similar to that shown in Fig. 1, and the same numerals have been used to 60 designate identical parts. In the arrangement shown in Fig. 2 a rotary type compressor 10 is provided with an upwardly extending casing 23 on which an electric driving motor 12 therefor is mounted. The compressor 10 and driving 65 motor 12 are mounted within a cylindrical hermetically sealed casing 17 made up of upper and lower sections 19 and 20, respectively, on a series of vertical helical compression springs 18. The upper and lower sections 19 and 20 of the hermetically sealed casing 17 are welded together at 70 21 and a reinforcing strip 22 is provided within the casing 17 and extends about the inner side of the seam 21. The upper ends of the supporting springs 18 are secured to laterally projecting feet 75

24 formed on the casing 23 by suitable bolts and plugs 25.

Vaporized gaseous refrigerant compressed in the compressor 17 passes from the discharge port thereof through a conduit 40, the upper end 41 of which communicates with the interior of the hermetically sealed casing 17. Compressed vaporized refrigerant within the casing 17 passes therefrom through a conduit 26 into the refrigerant circulatory passage 29 of the condenser 13 which surrounds the casing 17.

The condenser 13 is made up of complementary cylindrical inner and outer sheets of metal 27 and 28 having complementary indentations 30 and 31, respectively, formed therein. The indentations 30 and 31 define a refrigerant passage 29, and the sheets 27 and 28 are welded or otherwise rigidly secured together about their edges and between the indentations formed therein throughout their length. The refrigerant circulatory passage 29 is preferably divided into upper and lower sections which are connected in series by a conduit 32. The condenser 13 thus formed is supported on a series of radial heat-conducting fins 33 which extend between the outer side walls of the casing 17 and the inner walls of the condenser 13. The compressed vaporized refrigerant passing through the refrigerant circulatory passage 29 of the condenser 13 is cooled and liquefied by the transfer of heat therefrom to the cooling air which circulates upwardly over the surfaces of the condenser 13 and fins 33 due to natural draft. The refrigerant thus liquefied in the condenser 13 flows therefrom through a conduit 34 to a float valve 35 casing or chamber 14 in which it is accumulated.

A conduit 35 is provided which communicates with the interior of the float valve casing 14 above the normal liquid level therein, indicated by the dot-dash line 43, and with the interior of the hermetically sealed casing 17 above the level of the lubricating oil 35a accumulated in the lower portion thereof.

I provide an arrangement for inducing a flow of the fluid mixture of vaporized refrigerant and non-condensable gases in the casing 17 through the condenser 13. In the form of my invention illustrated in Fig. 2 the inner end of the conduit 26 is provided with a flared or funnel-shaped end portion 42 which surrounds the open upper end 41 of the compressor discharge conduit 40. The vaporized refrigerant compressed by the compressor 10 and discharged therefrom through the conduit 40 escapes in a stream from the outer end 41 of the conduit 40 at relatively high speed and enters the conduit 26. The stream of compressed gaseous refrigerant discharged from the conduit 40 into the conduit 26 entrains a portion of the fluid mixture of compressed vaporized refrigerant and non-condensable gases in the casing 17 and draws the same through the funnel-shaped end 42 of the conduit 26. The non-condensable gas and refrigerant in the condenser 13 are thus rapidly circulated therethrough due to the injector action of the compressor discharge conduit 40, and the non-condensable gas which collects in the float valve casing 14 above the normal liquid level therein is returned to the casing 17 through the conduit 35 due to the fluid circulation set up by the stream of compressed vaporized refrigerant discharged into the conduit 26.

The liquefied refrigerant accumulated in the float valve casing 14 is supplied therefrom through a conduit 36 to the refrigerant circulatory passages formed by indentations 37 in an

outer sheet of the sheet metal evaporator 15. The evaporator 15 is made up of inner and outer sheets of metal which are welded or otherwise rigidly secured together about the edges thereof and between the indentations formed therein, and a cylindrical longitudinal header 38 is formed in the upper portion of the evaporator 15. The upper ends of the passages formed by the indentations 37 communicate with the header 38 below the normal liquid level therein, the header 38 being ordinarily maintained about half full of liquid refrigerant. The liquid refrigerant in the evaporator 15 is vaporized by the absorption of heat from the contents of the compartment in which it is located, and the refrigerant thus vaporized is collected in the header 38 above the level of the liquid refrigerant therein. The vaporized refrigerant collected in the header 38 is returned to the intake port of the compressor 10 through a conduit 39. The cycle of operation above described is repeated and continued until the compartment in which the evaporator 15 is located is lowered to a desired value.

It will thus be seen that I have provided an improved method and arrangement by means of which an accumulation of non-condensable gases in the refrigerant circulatory passages of the condenser is prevented. As a consequence the condenser is able to operate efficiently and its passages will not become clogged with non-condensable gases.

Although I have illustrated two particular forms of my invention in connection with household type refrigerating machines, I do not desire my invention to be limited to the particular embodiments shown and described, and I intend in the appended claims to cover all modifications within the spirit of my invention.

What I claim as new and desire to secure by Letters Patent of the United States, is:

1. A refrigerating machine comprising a refrigerant compressor, a refrigerant condenser, means for supplying compressed vaporized refrigerant from said compressor to said condenser, means including a chamber for accumulating vaporizable liquid refrigerant liquefied in said condenser and non-condensable gases leaving said condenser, means communicating with said chamber above the normal liquid level therein for conveying non-condensable gases from said chamber and for mixing the non-condensable gases with compressed vaporized refrigerant leaving said compressor, means utilizing the flow of refrigerant from said compressor to said condenser for inducing a flow of non-condensable gases from said chamber to the means supplying compressed refrigerant to said condenser, a refrigerant evaporator, and means for supplying liquid refrigerant accumulated in said chamber to said evaporator.

2. A refrigerating machine comprising a hermetically sealed casing, a refrigerant compressor mounted in said casing, a refrigerant condenser, means for supplying compressed vaporized refrigerant from said compressor to said condenser, means including a chamber for accumulating vaporizable liquid refrigerant liquefied in said condenser and non-condensable gases leaving said condenser, means communicating with said chamber above the normal liquid level therein for returning non-condensable gases from said chamber to said casing, means utilizing the flow of refrigerant from said compressor to said condenser for inducing a flow of non-condensable gases from said chamber to the means supply-

- ing compressed refrigerant to said condenser, a refrigerant evaporator, and means for supplying liquid refrigerant accumulated in said chamber to said evaporator.
5. A refrigerating machine comprising a hermetically sealed casing, a refrigerant compressor mounted in said casing, said compressor having intake and discharge ports, said discharge port of said compressor communicating with the interior of said casing, said casing containing a fluid mixture of compressed vaporized refrigerant and non-condensable gases, a refrigerant condenser, means for supplying the fluid mixture in said casing to said condenser, means including a chamber for accumulating vaporizable liquid refrigerant liquefied in said condenser and non-condensable gases leaving said condenser, means communicating with said chamber above the normal liquid level therein for returning non-condensable gases from said chamber to said casing, means utilizing the flow of refrigerant from said compressor to said condenser for inducing a flow of non-condensable gases from said chamber to the means supplying compressed refrigerant to said condenser, a refrigerant evaporator, and means for supplying liquid refrigerant accumulated in said chamber to said evaporator.
4. A refrigerating machine comprising a hermetically sealed casing, a refrigerant compressor mounted in said casing, a refrigerant condenser, means for supplying compressed vaporized refrigerant from said compressor to said condenser, means including a float valve and a casing therefor for accumulating vaporizable liquid refrigerant liquefied in said condenser and non-condensable gases leaving said condenser, means communicating with said float valve casing above the normal liquid level therein for returning non-condensable gases from said float valve casing to said hermetically sealed casing, means utilizing the flow of refrigerant from said compressor to said condenser for inducing a flow of non-condensable gases from said float valve casing to said hermetically sealed casing, a refrigerant evaporator, and means for supplying liquid refrigerant accumulated in said float valve casing to said evaporator.
5. A refrigerating machine comprising a hermetically sealed casing, a refrigerant compressor mounted in said casing, said compressor being provided with intake and discharge ports, said discharge port of said compressor communicating with the interior of said hermetically sealed casing, said hermetically sealed casing containing a fluid mixture of compressed vaporized refrigerant and non-condensable gases, a refrigerant condenser, means for supplying the fluid mixture from said hermetically sealed casing to said condenser, means including a float valve and a casing therefor for accumulating vaporizable liquid refrigerant liquefied in said condenser and non-condensable gases leaving said condenser, means communicating with said float valve casing above the normal liquid level therein for returning non-condensable gases from said float valve casing to said hermetically sealed casing, and means utilizing the flow of refrigerant from said compressor to said condenser for inducing a flow of non-condensable gases from said float valve casing to said hermetically sealed casing.
6. A refrigerating machine comprising a hermetically sealed casing, a refrigerant compressor mounted in said casing, a driving motor for said compressor having a vertical shaft positioned above said compressor in said casing, said compressor having intake and discharge ports, said discharge port of said compressor communicating with the interior of said casing, a refrigerant condenser, means including a conduit for conveying compressed vaporized refrigerant from the interior of said casing to said condenser, and means including a cooling fan secured to the upper portion of said shaft of said driving motor and positioned in said casing and a conduit opening at the periphery of said fan for positively circulating vaporized refrigerant from the interior of said casing through said conduit and said condenser and for circulating cooling fluid over the surfaces of said motor and compressor.
7. A refrigerating machine comprising a hermetically sealed casing containing a fluid mixture of compressed vaporized refrigerant and non-condensable gases, a refrigerant compressor mounted in said casing, said compressor having intake and discharge ports, a refrigerant condenser, a conduit communicating with said condenser and with said casing, said conduit having a funnel-shaped end located within said casing, and means conveying compressed vaporized refrigerant from said compressor discharge port to said funnel-shaped end of said conduit for inducing a flow of the fluid mixture from said casing through said conduit and said condenser.
8. A refrigerating machine comprising a hermetically sealed casing containing a fluid mixture of compressed vaporized refrigerant and non-condensable gases, a refrigerant compressor mounted in said casing, said compressor having intake and discharge ports, a refrigerant condenser, a conduit communicating with said condenser and with said casing, said conduit having a funnel-shaped end located within said casing, and means conveying compressed vaporized refrigerant from said compressor discharge port to said funnel-shaped end of said conduit for inducing a flow of the fluid mixture in said casing through said conduit and said condenser, means including a chamber for accumulating vaporizable liquid refrigerant liquefied in said condenser and non-condensable gases leaving said condenser, and means communicating with said chamber above the normal liquid level therein for returning non-condensable gases from said chamber to said casing.
9. In a refrigerating machine having a hermetically sealed casing enclosing a compressor and containing a substantial quantity of non-condensable gas together with refrigerant discharged from said compressor, a condenser receiving compressed refrigerant from said casing, a chamber receiving liquefied refrigerant from said condenser and communicating above the normal level of liquid refrigerant therein with said casing, a method of preventing the accumulation of non-condensable gases in said condenser which comprises circulating refrigerant and non-condensable gases through said casing, said condenser and said chamber.

HARLEY H. BIXLER.
